UNITED STATES PATENT OFFICE.

JAMES J. HENNESSY, OF NEW YORK, N. Y.

LUBRICATOR.

Application filed October 17, 1923. Serial No. 668,995.

My invention relates to lubricators such as are adapted to be used in the journal boxes and driving boxes of railroad rolling stock and consists in an improved mechanism by 6 means of which the lubricant may be pumped from a suitable reservoir to the surface of the journal to which the device is applied.

The object of my invention is to provide 10 a simple reliable and durable pump operating mechanism and one in which the speed and capacity of different pumps may be varied by the change of a single part without affecting the remaining parts.

15 In prior patents issued to me, for instance, Nos. 1,378,452, 1,412,739, 1,412,740, 1,416,710, 1,423,850, and 1,423,851 I have disclosed pump operating mechanisms in which shifting of the journal longitudinally of its axis 20 operates the pump.

While such constructions are sufficient for many requirements there are operating conditions in which the projection of an operating member to the exterior of the box is 25 objectionable and in which the movement of the pump plunger in one direction should be quicker than that provided by the shifting movement of the journal through the box, which may be very slow.

30 Other objects of my present invention are to satisfy these requirements.

In the accompanying drawings which illustrate my invention—

Figure 1 is a vertical transverse section 35 through a journal to which my lubricator is applied.

Figure 2 is a vertical longitudinal section through my lubricator showing the journal.

Figures 3 and 4 are vertical transverse 40 sections corresponding to Figure 1 but taken through modified embodiments of my invention.

Figure 5 is a detail illustration of the 45 pawl and lever shown in Figure 1, but indicating a different position of the same.

In Figure 1 the lower portion of the journal lubricator body 1 forms a lubricant reservoir 2 and suitable horizontal surfaces 3 and 4 on the body carry springs 5 which 50 support a pan 6 adjacent to the journal A, which pan is adapted to be packed with waste or other lubricant retaining and distributing material.

Extending from the lower portion of 55 reservoir 2 to a central opening in pan 6 is a passage 7 equipped with an intake valve

8 and a check valve 9 between which is located the mouth of a pump cylinder 10, the piston or plunger 11 of which cylinder is slidably mounted therein and in a suitable 60 bearing 12 spaced from the cylinder and forming a seat for a spring 13 which tends to force the piston through its discharge stroke to an advanced position in the cylinder. The piston is operated through its 65 intake stroke by means of a cam 14 and a bell crank 15 and a simple lever 16. The cam 14 is fixed upon a rotatable shaft 17 journaled in housing 1 and carrying spaced disks 18 which partially support a roller 19 70 adapted to engage the surface of journal A above a horizontal line passing through the journal axis and to be frictionally rotated by the journal so as to drive disks 18, rod 17 and cam 14.

A rod 20 passes through a relatively large axial opening in roller 19 and retains the roller in operative position without limiting its actual position leaving the roller free to accommodate variations in the axes and 80 relative positions of the disks 18 and journal A. Obviously rotation of cam 14 in the direction indicated by the arrow in Figure 1 will move the horizontal leg of crank 15 downwardly. A weighted pawl 22 pivoted on the inner end of this leg of the bell crank engages a pin 23 on the bell crank so as to be held against pivotal movement in one direction and downward movement of the bell crank causes the end of this pawl 90 22 to engage the inclined surface on the end of lever 16 thrusting the same to the left and retracting piston 11 through cylinder 10. As soon as the point 24 upon lever 16 rides over the top of pawl 22 the lever 95 is released and spring 13 will quickly move it and piston 11 to their original positions thereby providing the pump with a quick discharge stroke forcing lubricant upwardly along passage 7 to the surface of the 100 journal. When the vertical leg of bell crank 15 is released by the cam a spring 25 returns it to its original position and in so doing pawl 22 is turned on its pivot until its lever engaging end has ridden over point 105 24 when it will return to its normal position in engagement with pin 23. Obviously movement of the cam in the opposite direction will raise the horizontal leg of the bell crank from the position shown in Figure 110 1 without operating the pump.

It will be noted that body 1 is provided

with an upwardly and inwardly extending portion which houses the cam, disks and roller and protects them from damage before and during their installation and operation in the journal box.

In the construction shown in Figure 3 the pump cylinder 30 and piston 31 are vertically disposed and the upper end of the piston is directly engaged by cam 32 and will be operated by movement of the cam in either direction. In this operation the quickness of the return of the plunger to the position shown will be limited by the speed at which the cam is driven and by the angle necessary to permit the piston to be depressed. In this construction the remaining features of the device correspond to those illustrated in Figure 1 although somewhat differently arranged.

In the construction shown in Figure 4 a one-way drive for the pump is illustrated in which the cam 33 is rotated by a roller 34 similar to the cam and roller arrangement in Figures 1, 2 and 3. The bell crank

35 which is operated by cam 33 is directly connected to horizontal piston 36 which is disposed similarly to piston 11 in the construction shown in Figure 1. Here a quick return or discharge movement of the piston is provided for by the contour of cam 33. It is obvious that this quick movement of the piston may be provided for the intake stroke instead of the discharge stroke if desired. In the construction shown in Figure 4 this may be accomplished by reversing the cam and extending the horizontal arm of the bell crank to the right instead of to the left and moving its pivotal point accordingly and in the construction shown in Figure 1 by reversing the inclined end of lever 16 so that it faces the left instead of the right and by reversing pawl 22 on the bell crank and moving it to the other side of lever 16.

The engagement of the cam and bell crank in the construction shown in Figure 4 is so arranged that reversal of the direction of rotation of the cam from that indicated by the arrow will be accommodated. An L-shaped contact finger 39 is pivoted on the end of bell crank 35 so that when its horizontal leg engages the bell crank a rigid elevated cam-engaging element is provided whereby the bell crank is actuated. When the offset portion 40 of the cam strikes finger 39 from the left, the finger is free to turn to the dotted line position and permit the cam to rotate without operating the bell crank.

In the construction shown in Figure 4 the intake valve is omitted and a number of small openings 37 are provided in the wall of the pump cylinder. With a slow intake stroke of the piston these openings will admit lubricant sufficiently quick enough to

fill the cylinder. With the quick discharge stroke of the piston the check valve 38 will be lifted and a substantial amount of lubricant forced by the same and the piston will pass openings 37 before any substantial amount of lubricant has been expelled through them.

In any of these constructions any obstruction of the device due to clogging of the pump or positive engagement of the parts caused by reversal of the direction of rotation of the journal will simply result in the rotation of the idle roller without corresponding rotation of the disks thus avoiding any injury to the device.

In all of my above described constructions the speed and capacity of the pump may be readily controlled by varying the weight and size of the loose roller contacting with the journal and pump driving disks.

Various other modifications in the details of construction may be made without departing from the spirit of my invention as expressed in the appended claims.

I claim:

1. In combination, a journal, a lubricant reservoir, a lubricant supply pump, a rotatable member for operating said pump, and a floating roller carried solely by said journal and member in frictional contact with said journal and member for actuating said member from said journal.

2. In a journal lubricator, a pump including a reciprocating piston, a spring tending to move said piston in one direction, a rotatable cylinder having a cam, means actuated by said cam to move said piston in the opposite direction, and a floating rotatable member carried by said cylinder and by the journal to which the lubricator is applied for driving said cylinder to operate said cam.

3. In a journal lubricator, a pump, a rotatable pump operating member having an axis parallel to the axis of the journal to which the lubricator is applied, and a rotatable idler for actuating said member from said journal and adapted to be supported solely by said member and journal.

4. In a journal lubricator, a body adapted to be inserted in the cellar of a railway journal or driving box, a pump cylinder therein, a pump piston reciprocal in said cylinder, a piston operating member journaled in said body, and a floating element for engaging said member and the journal to which the lubricator is applied to actuate said member by movement of said journal.

5. In a journal lubricator, a body adapted to be inserted in the cellar of a railway journal or driving box, a pump cylinder therein, a pump piston reciprocal in said cylinder, a rotatable piston operating member journaled in said body, a rotatable member loosely retained in said body and adapted to en-

gage said member in different positions about the periphery of the latter and to engage a journal to which the lubricator is applied to actuate said member from said journal.

6. In combination, a journal, a lubricant reservoir, a pump for feeding lubricant from said reservoir to said journal, a rotatable member for operating said pump spaced from said journal with its axis parallel to the journal axis, and a floating idler supported by said member and journal and rotated by the latter to rotate the member.

7. In a journal lubricator, a body forming a lubricant reservoir, a pump therein, pump actuating mechanism a substantial distance above said reservoir and pump and adapted to contact with a journal to which the lubricator is applied, and an upward and inward extension on said body forming a housing for said mechanism.

8. In a journal lubricator, a pump, a

pump operating rotatable cam having its axis parallel to the axis of the journal to which the device is applied, spaced disks on opposite sides of said cam coaxial and rotatable therewith and larger in radius than the greatest cam radius, and an idler roller adapted to rest upon said disks and the journal to which the device is applied so as to frictionally rotate the disks from the journal.

9. In a journal lubricator, a lubricant pump, a lever for operating said pump having an end with an inclined surface provided with an offset at one end, a reciprocal member for operating said lever including a pawl pivoted thereon, and a pin preventing movement of the pawl in one direction, said pawl being adapted to engage said lever surface.

In testimony whereof I hereunto affix my signature this 14th day of September, 1923.

JAMES J. HENNESSY.
